CHARLES P. BROWN

ATTORNEY

UNITED STATES PATENT OFFICE.

CHARLES P. BROWN, OF SEATTLE, WASHINGTON.

SAND-FEEDING APPARATUS.

1,197,102.

Specification of Letters Patent. Patented Sept. 5, 1916.

Application filed January 13, 1916. Serial No. 71,980.

To all whom it may concern:

Be it known that I, CHARLES P. BROWN, citizen of the United States, residing at Seattle, in the county of King and State 5 of Washington, have invented certain new and useful Improvements in Sand-Feeding Apparatus, of which the following is a specification.

This invention has particular relation to 10 sand feeding apparatus and as its primary object it contemplates the provision of an improved device of this character that is especially designed to be used in connection with automobiles and other motor vehicles 15 and which will apply the sand to the ground so as to prevent lateral as well as the longitudinal skidding of the machine.

Another object of the invention is to provide improved means for efficiently feeding 20 the sand to the various distributing nozzles in order that a uniform flow may be obtained at all times, when desired, and to obviate stoppage of the sand due to the clogging of the conducting pipes.

25 A further object of my invention is to provide a device of the type in question that is extremely simple in construction, strong and durable, and highly practical from both the standpoint of the manufacturer and the 30 standpoint of the user; and which, it is believed, may be manufactured at a comparatively low cost.

35 Various other objects and advantages will become apparent during the continuance of the following description.

These objects are accomplished by such means as are shown in their preferred form in the accompanying drawings, described in the following specification and then more 40 specifically pointed out in the appended claim.

In the accompanying drawings wherein like characters designate like parts throughout the several views: Figure 1 is a view 45 in top plan showing my invention as applied to an automobile of substantially the conventional form, the automobile body being shown in dotted lines; Fig. 2 is a view in longitudinal section of one of the distributing chambers; Fig. 3 is a view of the sand dome or reservoir; and Fig. 4 is a diagrammatic view illustrating the relative position of the distributing nozzle and the respective wheel.

55 In reducing my invention to practice, I provide a dome or reservoir 10 to receive

the bulk of sand, and which may be secured at any desired place on the vehicle body. Upon its under side, the dome 10 is provided with a series of individual chutes 11 which may be in turn connected with the several feeding pipes 12, 13 and 14 respectively. Suitable distributing chambers may be arranged in proximity to each of the drive wheels of the machine while a single distributing chamber may be used in common in connection with the front wheels thereof.

In Fig. 1, the several distributing chambers are designated by the numerals 15, 70 16, and 17, respectively; however, in view of the fact that they are all of practically the same construction, only one will be described in detail. This distributing chamber is shown in section in Fig. 2.

The distributing chamber above referred to, consists of a tubular body structure 18 that may be formed of any suitable or desirable material, and which is preferably constricted slightly toward one end to form 60 an annular offset flange 19. At its other end, the respective casing may be formed so as to receive a plug 20, the latter having an air passage 21 and a nozzle member 22 associated therewith such as clearly shown. 65 The casing 18 is further provided with an inlet opening 23 about which is arranged a connecting collar 24, the inlet opening extending at a substantially right angle with respect to the general extent of the casing, 90 in its preferred embodiment. The lower ends of the several feeding pipes 12, 13 and 14, as above referred to, may be provided with suitable flanges 25 whereby they may be readily connected with the collar 24 of 95 the several distributing casings. Furthermore, in order to facilitate a more secure connection between the feed pipes and the casings, it has been found desirable, under certain conditions, to interpose a washer or 100 take-up member 26 between the flange and the collar. This take-up member also serves to rotatably support the flange 25 as clearly shown in Fig. 3. Adjacent the passage 21, the plug 20 is provided with an annular offset 105 26 to which may be connected one end of a conducting tube 27. I preferably provide a conducting tube for each of the distributing chambers, such as indicated by the numerals 27, 28, and 29 which in turn connects with an air container or other generative source, as at 30, by way of a suitably con-

trolled regulating valve 31. Consequently, when desired, the operator may open the valve 31 so as to permit the air from the casing 30 to be introduced into the several distributing chambers such as is obvious.

Distributing pipes 32, 33, 34 and 35 respectively, are connected with the several casings 15, 16 and 17 such as clearly shown in Fig. 1, and which in turn carry suitable nozzles 36 by which the sand may be properly distributed about the ground in advance of the wheels. The pipes 32 and 33 may be arranged so that the nozzles 36 carried thereby direct the sand onto the ground 10 slightly in advance of the side wheels and by reason of the special configuration of the nozzles, the sand will be spread in a fan-shape manner about the ground. This, as will be apparent, will effectually prevent lateral skidding of the wheels as well as longitudinal skidding thereof. On the other hand, the pipes 34 and 35 which project from the casings 17 are arranged so that the sand ejected therefrom will be placed 20 in advance of the front wheels and to each side thereof whereby skidding thereof will be effectually prevented, irrespective of the angle at which the wheels may be turned. Skidding generally occurs when the machine is rounding a curve and this method of distributing the sand is thought to be especially effectual in this connection.

Although any desirable means may be employed by which the operator can control the valve 31 above referred to, it is pointed out that this may be controlled by a switch in proximity to the operator's post of duty. Consequently, in the drawing I have shown suitable conductors 37 and 38 connected 30 with the valve, while one is connected with one pole of the source of power 39. The other conductor 38 is in turn connected with a switch pole 40 while another conductor 41 connects with the other pole of the source of power 39 and the switch lever 42. Consequently, by closing the switch lever in the usual manner the valve 31 may be opened or closed such as the case will be.

Under normal conditions, the sand from the dome 10 is fed by action of gravity into the respective distributing chambers, as shown in Fig. 2, so as to completely cover

the nozzle member 22, therefore, when the air is introduced through the nozzle member, the sand in the forward or rear end of the chamber, such as the case may be, will be forced directly through the respective distributing pipes, while, at the same time a partial vacuum will be formed, such as will tend to create a continuous flow of sand 60 from the feed pipes into the casing. Consequently, it will be seen that a combined force feed and suction will be obtained, each acting in co-operation with each other.

From the foregoing, it is believed, that the advantages and novel features of my invention will be readily understood and, therefore, further detail description is deemed unnecessary.

In reducing my invention to practice I find that the form referred to herein as the most practical and preferred embodiment is the most efficient, but realizing that certain conditions will necessarily vary in concurrence with the adoption of my device, I desire to emphasize the fact that various minor changes in the details of construction and in the proportion of parts may be resorted to when required without sacrificing any of the advantages of my invention as defined in the appended claim.

Having thus fully described the invention, what I claim as new and desire to secure by Letters Patent is:—

In a sand feeding apparatus, a distributing chamber comprising a hollow elongated conical body, an intake communicating with said body at a point adjacent to and spaced from the larger end of said body, an outlet open to the smaller end of said body, a removable plug fitting the inner wall of said body, and a nozzle carried by said plug terminating at a point approximately intermediate the ends of said body; whereby the larger end of said body forms a compartment in the rear of the mouth of said nozzle serving as an auxiliary chamber for the sand.

In testimony whereof I affix my signature in presence of two witnesses.

CHARLES P. BROWN.
